DRILLING MECHANISM

Russell H. Wilhelm, Easton, Pa., assignor to Ingersoll-Rand Company, Jersey City, N. J., a corporation of New Jersey

Application July 20, 1933. Serial No. 681,232

3 Claims. (Cl. 255—45)

This invention relates to drilling mechanism, and more particularly to drilling mechanism equipped with means for preventing rebound of the rock drill with respect to its support in order 5 that the rock drill may be either advanced toward the work or retracted therefrom by the jar resulting upon reversal of its piston.

One object of the invention is to enable the drilling motor to be advanced and retracted upon 10 the support with a single manual setting of the recoil arresting device.

Other objects will be in part obvious and in part pointed out hereinafter.

In the drawing accompanying this specification 15 and in which similar reference numerals refer to similar parts,

Figure 1 is a longitudinal side elevation of a drilling mechanism constructed in accordance with the practice of the invention and showing 20 the recoil arresting device in one limiting position,

Figure 2 is a similar view showing the recoil arresting device in another limiting position, and

Figure 3 is a perspective view illustrating more 25 particularly the manner in which the recoil arresting device is held in one of its limiting positions.

Referring more particularly to the drawing, 4 40 designates a rock drill equipped with a carriage 5 mounted slidably upon a support 6.

The support 6 may, as indicated, be of structural shape, as for instance an I-beam, and in the opposite sides of the carriage 5 are guideways 7, only one of which is shown in Figure 3, to receive the flange 8 of the support 6 and whereon the carriage 5 slides. The rock drill 4, which may be of any well known type, has the usual front and back heads 9 and 10 which may be secured to a cylinder 11 by side rods 12, in the usual manner.

The front head 9 acts as a guide for a working implement 13, such as a drill steel, and within the cylinder 11 is a reciprocating hammer piston 14 to strike against the working implement 13 for 45 driving it into the work.

The pressure fluid utilized for actuating the piston 14 may be distributed to the ends of the cylinder 11 by any suitable form of distributing valve (not shown) and communication between 50 the distributing valve and the source of pressure fluid supply may be controlled by a throttle valve only the lever 15 of which is shown.

In accordance with a well known practice the drilling motor 4, or more particularly the carriage 5 carrying the motor, is provided with means

adapted to alternately seize and release the flange 8 of the support 6 to enable the rock drill to be actuated longitudinally of the support 6. The means illustrated for this purpose comprises a link 16 having a gripping portion 17 adapted to grip the flange 8 and a stem 18 of which the free end extends into an aperture 19 in a bracket 20 constituting the rear end of the carriage 5. The aperture 19 is preferably of somewhat larger dimensions than the portion of the stem 18 lying therein so that the link 16 may be readily tilted to its various gripping positions.

The means provided for positioning the link 16 comprises a shaft 21 journaled in the bracket 20 and having a crank pin 22 which pivotally engages the end of a rod 23 extending through the link 16 and having a nut 24 threaded on its free end. Disposed on the rod 23 and on opposite sides of the link 16 against which they seat are springs 25 and 26 to hold the link 16 yieldably in position for gripping the flange 8. The shaft 21 may, as shown, be provided with a suitable grip element 27 for rotating the shaft and consequently to actuate the link 16 to its limiting positions.

In accordance with the practice of the invention means are provided for holding the link 16 positively in gripping relation with respect to the flange 8 to assure continuous movement of the rock drill 4 in the direction of the work and also to automatically effect reversal of the link when the rock drill 4 reaches a position wherein the working implement 13 has penetrated the work to the limit of its extent. To these ends the carriage 5 is provided with a latch 28 adapted to engage a detent 29 in the outer end of the shaft 21. The latch 28 is pivoted upon a pin 30 carried by the carriage 5 and has a depending arm 31 which, when the carriage 5 moves forwardly, engages an abutment 32 near the front end of the support 6 for tripping the latch to disengage the detent 29.

The outer end of the shaft 21 is preferably in the form of a drum 33 for the accommodation of a flexible element, such as a chain 34, which is connected with one end to the drum by a screw 35. The other end of the chain 34 engages an end of a tension spring 36 which extends forwardly along the rock drill 4 and is hooked to a washer 37 arranged on a bolt 38 extending through a boss 39 of the carriage 5 and which bolt may serve to clamp the rock drill to the carriage.

On or near the rear end of the support 6 is an arm 40 which extends with its free end 41

into the path of the throttle lever 15 so that when the drill reaches the rear end of the mounting the said lever 15 will abut the arm 40 and, as the rock drill continues in a rearwardly direction, the throttle valve which the lever 15 controls will be closed to cut off the flow of pressure fluid to the rock drill.

The operation of the device is as follows: Let it be assumed that the rock drill 4 occupies its 10 rearmost limiting position on the support 6 and that it be desired to cause it to be actuated forwardly along the support in the direction of the work. The shaft 21 may then be rotated to the left hand position as Figure 1 is viewed. Thus 15 positioned the latch 28 engages the detent 29 and the spring 26 will be compressed so that it will maintain the link 16 constantly in position to grip the flange 8. During the subsequent operation of the rock drill 4 the jar resulting upon 20 reversal of the piston 14 in the front end of the cylinder 11 is imparted to the rock drill, thereby causing the rock drill, together with the carriage 5, to be shifted forwardly. Upon reversal of the piston 14 in the rear end of the cylinder the 25 shock of reversal will cause the gripping portion 17 to seize the flange 8 and prevent recoil of the rock drill.

As the rock drill proceeds forwardly and about the time the working implement 13 has penetrated the rock to the limit of its extent the arm 30 31 of the latch 28 engages the abutment 32 which trips the latch 28 to release the detent 29. The spring 36 which, during the forward movement 35 of the drill, is tensioned will then contract and, by rotating the shaft 21, shift the link 16 rearwardly to its other limiting position. This action 40 of the spring 36 will also place the spring 25 on the rod 23 under compression so that the gripping portion will be held constantly in position for engaging the flange 8 of the support 6.

With the parts in the new positions described and with the rock drill 4 continuing its operation the rock drill and the carriage will be moved rearwardly by the jars imparted thereto by the 45 piston 14 upon reversal thereof in the rear end of the cylinder. Upon reversal of the piston in the front end of the cylinder the link 16 will, by its gripping engagement upon the flange 8, maintain the rock drill immovable with respect to the 50 support 6. The rock drill and the carriage will, therefore, be retracted toward the rear end of the support 6 and upon contact of the throttle lever 15 with the end 41 of the arm 40 the throttle valve will be rotated to its closed position and in 55 that way cut off the supply of pressure fluid to the rock drill.

In practice the present invention has been

found to operate with certainty and with a minimum of attention on the part of the operator since, as will be readily understood, it is merely necessary to set the recoil arresting device in position for advancing the drill toward the work. 80 Simultaneously with the setting of the parts to bring about this result the spring 36 is tensioned so that, upon release of the latch 28 from the 85 detent 29, it may act to reverse the recoil arresting device. It will be obvious, therefore, that after the drill has been set in operation it will proceed both towards the work and return to its initial starting position without further attention on the part of the operator.

I claim:

1. In a drilling mechanism, the combination of a support and a percussive motor thereon subjected to jars incident to its operation tending to move the motor along the support, recoil arresting means for the motor, latch means for locking the recoil arresting means in one limiting position, means for tripping the latch means to disengage the recoil arresting means, and means carried by the percussive motor acting to reverse the recoil arresting means upon disengagement 100 of the latch means from the recoil arresting means.

2. In a drilling mechanism, the combination of a support and a percussive motor thereon subjected to jars incident to its operation tending to move the motor along the support, recoil arresting means for the motor, a shifting device for the recoil arresting means, latch means to engage the shifting device for holding the recoil arresting means in one limiting position, and 110 means acting to move the shifting device for shifting the recoil arresting means to another limiting position upon disengagement of the latch means from the shifting device.

3. In a drilling mechanism, the combination 115 of a support and a percussive motor thereon subjected to jars incident to its operation tending to move the motor along the support, means carried by the motor and being adapted to engage the support to prevent rebound of the motor, a shifting device for actuating the said means to limiting positions, a spring connected to the shifting device and the motor, a latch to engage the shifting device for holding the said means in one limiting position and to maintain the spring 120 under tension, and an abutment on the support to trip the latch out of engagement with the shifting device, thereby enabling the spring to actuate the shifting device and thus move the said means to another limiting position.
